CANDELABRUM SOCKET

Carl M. Petersen, Trenton, N. J., assignor to
Circle F Mfg. Co., Trenton, N. J., a corporation
of New Jersey

Application October 25, 1932, Serial No. 639,510

5 Claims. (Cl. 240—52.4)

This invention relates to candelabrum sockets and more particularly to an improvement in sockets of the so-called adjustable type.

Heretofore it has been the general practice to 5 use a threaded fastening or screw for locking together the arms of the extensible bracket elements. This practice has required the parts to first be set to the desired height and then the use of a screw driver or other tool to secure the parts 10 in their adjusted position. Not only is this practice tedious because of the several operations involved but frequently after the workman sets the parts in their adjusted relation under the present practice they will slip or slide while he is manipulating the screw locking means.

Accordingly, a primary object of the invention is to obviate the disadvantages incident to the practice above outlined and to provide a novel means for locking the adjustable or extensible 20 parts quickly in adjusted relation. That is to say, according to the present invention, after the brackets which support the socket have been attached to the fixture, they can be adjusted with one hand to the desired height and with the 25 thumb or finger of the same hand which does the adjusting, they may be quickly and securely locked in adjusted position.

A further object of the invention is to provide 30 simple, practical and reliable means for locking the bracket parts together which will not only quickly and securely hold them in adjusted position, but if it later becomes necessary to readjust the parts, such readjustments can be readily effected by the same simple finger manipulation 35 which was utilized to effect locking.

A further object of the invention is to provide 40 a candelabrum socket structure which does not require the use of any tools to effect its mounting or adjustment.

With the above and other objects in view which 45 will more readily appear as the nature of the invention is better understood, the invention consists in the novel features of construction, combination and arrangement of parts as will be hereinafter more fully described, illustrated in the accompanying drawing and defined in the appended claims.

A preferred and practical embodiment of the 50 invention is shown in the accompanying drawing, in which:

Figure 1 is a front elevation of the improved construction.

Figure 2 is a side elevation.

Figure 3 is a horizontal section taken on the 55 line 3—3 of Figure 1.

Figure 4 is a view similar to Figure 3 illustrating the position of the locking means in unlocked position.

Figure 5 is a detail perspective view of the locking lever.

Similar reference characters designate corresponding parts throughout the several figures of the drawing.

As previously indicated the present invention 65 provides a novel finger manipulated lock for securing the parts of the supporting bracket together. To that end the locking lever A is provided, the same being so mounted and arranged that when it is in a substantially horizontal position, for example, the bracket parts may be freely 70 adjusted, but when the lever is turned to a position above or below horizontal, thereby to lie in close proximity to the adjustable members, the latter are held securely locked.

In the drawing, the fixture engaging bracket B 75 and the socket carrying bracket C are arranged in overlapping or telescopic relation, one of said members being provided with a slot and the other with a guiding pin operating in the slot. In the example shown the socket carrying member C is 80 provided with the slot 1 and the fixture engaging member B is provided with the cross-member or guiding pin 2. The latter is provided at its outer ends with the head portions 3—3 which provide 85 abutments for the side arms of the bracket B to prevent separation thereof under pressure of the locking lever A as will presently appear.

The said locking lever A is provided at one end 90 with a sleeve 4 or its equivalent which fits over the pin 2 in such a way that the lever may have a free swinging movement about the pin. The ends of the sleeve 4 adjacent the arms of the socket carrying bracket C are provided with the cam projections 5—5, which in one position of the lever A are adapted to register with the slots 95 1—1 in the arms of the members C, and in another position are adapted to engage the inside faces of the arms of the members C and force the arms into binding engagement with the arms of the member B, the said latter arms being held against outward expansion or separation by reason of the heads 3 on the ends of the pin 2.

When the lever A is in the full line position 105 shown in Figures 1, 2 and 3, it will be apparent that the cam elements 5 force the arms of the brackets B and C into locking engagement. On the other hand, when the lever A is in the dot and dash line position A' (Figure 2) it will be understood that the cam elements 5 are in the 110

position shown in Figure 4 to permit the adjustment of the members B and C.

Since the cam projections 5—5 are disposed at diametrically opposite points on the ends of the sleeve 4, it will be apparent that the lever A may be swung upwardly or downwardly, away from the horizontal, for the purpose of effecting the locking together of the extensible parts.

From the foregoing, it will be apparent that the present invention provides a simple and practical form of cam locking means for readily and quickly securing the extensible bracket parts of a candelabrum socket together, without the use of tools and with a minimum of time and effort, while at the same time making adjustment more accurate.

Without further description it is thought that the features and advantages of the invention will be readily apparent to those skilled in the art, and it will of course be understood that changes in the form, proportion and minor details of construction may be resorted to, without departing from the spirit of the invention and scope of the appended claims.

25 I claim:

1. A candelabrum socket including a pair of U-shaped bracket members having overlapping arms, the arms of one member being slotted, a pin carried by the other member and riding in the slots, abutment means on the ends of the pin, and a shiftable locking lever carried by the

portion of the pin between the slotted arms of one of the brackets, said shiftable lever having means releasably to lock said arms in adjusted position.

2. In a candelabrum socket, adjustable members connected by a cross member, and a lever actuated cam mounted on said cross member for locking said members in selected adjusted position, said cam having its axis of rotation coincident with the axis of the cross member.

3. In a candelabrum socket, adjustable members connected by a cross member, and a lever mounted on said cross member and having cam projections adapted in different positions of the lever to force the adjustable members into locking engagement.

4. In a candelabrum socket, adjustable members, a cross pin for preventing separation of the members, and a lever mounted on one of the members and having cam projections for forcing the adjustable members into locking engagement at any selected point within the range of maximum movement permitted by the cross pin.

5. In a candelabrum socket, adjustable members, a cross pin for preventing separation of the members, a lever having a sleeve portion journaled on the pin, and cam projections carried by each end of the sleeve for forcing the adjustable members in locking engagement in different positions of the lever.

CARL M. PETERSEN.
